UNITED STATES PATENT OFFICE.

JACOB W. KAISER, OF CLEVELAND, OHIO.

FASTENING DEVICE.

1,295,515.

Specification of Letters Patent. Patented Feb. 25, 1919.

Application filed November 22, 1916. Serial No. 132,744.

To all whom it may concern:

Be it known that I, JACOB W. KAISER, a citizen of the United States, residing at Cleveland, in the county of Cuyahoga and State of Ohio, have invented a certain new and useful Improvement in Fastening Devices, of which the following is a full, clear, and exact description.

This invention relates to a locking and fastening device by which two parts having sliding relationship with each other may be slid one over the other until in certain registering position when the locking device becomes effective and holds them locked in their relative position.

Among other uses to which the invention may be put I may mention that of securing and locking a cap upon the neck of a bottle, or holding a sleeve or ferrule on the neck of a bottle.

Generally speaking, the invention may be said to comprise the elements and combinations thereof, set forth in the accompanying claims.

Reference should be had to the accompanying drawings forming a part of this specification, in which Figure 1 shows partly in elevation and partly in section the neck of a bottle having a cap in connection with which this invention may be employed; Fig. 2 is a section on the line 2—2 of Fig. 1; Fig. 3 is a transverse section through the cap along the line 2—2 of Fig. 1; and Fig. 4 shows another construction in which the locking device of this invention may be used.

In many constructions it is desirable to place a cap or similar member upon the neck of a bottle and to lock the cap or cylindrical member so that it can not be removed without destroying the bottle. This is useful where it is desired to prevent the original contents of the bottle from being disturbed until it is used, and necessitating the practical destruction of the bottle or container when the contents is removed.

For instance, liquids shipped in bottles, if provided with a cap and locking device as shown in this application, could not be tampered with, and the only way in which the contents of the bottle could be removed would be breaking the neck of the bottle. This would so damage the bottle that it could not be again used, and consequently would effectually prevent refilling of the bottle. Of course, in addition a cap may be

used which will effectually seal the bottle against the admission of air.

Referring to the drawings, 1 represents the neck of a bottle which is provided with a groove in the exterior surface thereof, as indicated at 3. This groove extends around the bottle and is of sufficient depth to receive the locking spring later to be described. The cap member 4 which fits over the head of the neck of the bottle may upon the inside have a washer 5 which fits between the cap and the top of the bottle thus effecting a seal so as to prevent the admission of air or dust into the interior of the bottle.

The cap upon the interior surface thereof is provided with a groove 6, which is in proper position to align with the groove 3 when the cap is in proper position upon the bottle. This groove is preferably formed, as indicated in Fig. 3, that is to say, the groove is not a continuous groove but is in reality made up of four grooves. Each groove varies in depth from the deepest part until the wall of the groove is tangent with the inner surface of the cap. Between the two oppositely disposed grooves there are projections 8 which serve in a manner about to be described.

Within the groove 3 there are two spring elements 9. Each of these spring elements are the same and are so made that they tend to expand outwardly or away from the neck of the bottle. In assembling the cap upon the bottle the resilient members 9 are placed in the groove 3 upon the neck of the bottle, and are held in until the lower portion of the cap begins to slide over the groove 3. The cap will then temporarily hold the spring 9 within the groove 3. When, however, the groove 6 comes to a position opposite the groove 3, the ends of the spring will immediately move away from the neck of the bottle and into the grooves 6 which are formed in the cap 4. The central portion of the resilient members can not move out of the groove 3 because it will be noted from Fig. 3 and the description thereof, that the grooves 6 are at certain places tangent to the inner wall of the cap 4, and these places where the wall of the groove 6 is tangent are substantially in line with the central portion of the resilient members 9.

The lugs 8, it will be seen, separate adjacent ends of the two springs. Therefore, if the cap 4 be turned, the springs will

simply move around as the cap is turned, but there will be no opportunity to work the springs past each other and thus perhaps make one or more of the springs inoperative as a locking spring.

The cap when thus locked to the neck of the bottle is, practically speaking, unremovable without destroying the neck of the bottle, and this forms an effective lock.

10 In Fig. 4 I have shown another application for the locking device. In some instances it is desired to attach a fixture to the end of a bottle. I may mention as an example of such a fixture, a device which 15 will permit the contents of a receptacle or bottle to be emptied, and which will prevent the refilling of the bottle. These devices are usually made separately from the bottle to which they are to be attached, and 20 it is common practice to hold the device upon the bottle by spinning or otherwise securing a metal band upon the neck of the bottle and upon the lower portion of the non-refillable device.

25 It is, however, a very simple matter for a good mechanic to remove such a ferrule and after refilling the bottle, again spin a ferrule to hold the non-refillable attachment to the bottle and to make so neat a job of 30 it that it would not be detectable, at least by the average person.

The lock disclosed in this application may be utilized to hold the non-refillable attachment to a bottle and effectually prevent any 35 such tampering as has heretofore been described.

In this connection, the neck of the bottle 10 is provided with a groove 11, the groove 11 being an annular groove of the same general description as the groove 3. The non-refillable device which is designated at 12, is as here shown, provided with a shoulder 13 which is adapted to be engaged by a ferrule 14. This ferrule is preferably of porcelain 45 or similar material, or of heavy metal so that it may not be tampered with without damaging it.

In the lower portion of the ferrule 14 is a groove 15. This groove is similar in all respects to the groove 6 which is shown in cross-section in Fig. 3. The springs 16 co-operate with the grooves 11 and 15 in the same manner as that described with respect to the grooves 3 and 6. Thus it will be seen that the ferrule 14 and the part 12 held thereby, are locked relative to each other.

It will be apparent that other means than a ferrule may be used to hold the non-re-

fillable device to the neck of the bottle, as 60 for instance, the ferrule 14 and the non-refillable device may be formed as one piece.

Having thus described my invention, what I claim is:—

1. The combination of two telescoping 65 members which slidably engage each other, a groove formed in each of said members upon the surfaces which engage, the groove in one of said members having deep end portions and a central portion which extends 70 outwardly and is substantially tangent to the surface of the other member, and a spring having ends which are adapted to spring outwardly and occupy the deep portions of the groove last mentioned, the center portion of the spring occupying a part of the other of said grooves and substantially opposite the tangential part of the said groove whereby the cylindrical members are 75 locked against sliding movement. 80

2. The combination of two telescoping members which slidably engage each other, a groove formed in one of said members which is of substantially uniform depth, a groove formed in the other of said members 85 which has deep end portions, and a central portion which is substantially tangent to the inner wall of the member in which it is formed, and a flat spring the end portions of which spring outwardly and occupy the 90 deep portions of the said groove the central portion of the spring occupying part of the groove of uniform depth and said central portion of the spring being oppositely disposed with respect to the tangential part of 95 the said groove.

3. The combination of two telescoping members which slidably engage each other, the grooves formed in said members upon the surfaces which engage, one of the members having two grooves, each of the grooves being deeper at their end portions while at the middle the groove portion is tangential to the surface of the member in which it is formed, projecting members separating the 105 deep portions of the separate grooves from each other, and springs, each of which springs has end portions that are adapted to occupy the deep portions of one of the said grooves, the central portion of each 110 spring occupying a part of the other of said grooves and oppositely disposed with respect to the tangential part of the before mentioned grooves whereby the cylindrical members are locked against sliding movement. 115

In testimony whereof, I hereunto affix my signature.

JACOB W. KAISER.
